CARBONATOR APPARATUS

Carmelo V. Di Pietro, Birmingham, Mich.

Application February 3, 1944, Serial No. 520,995

7 Claims. (Cl. 261—11)

1

This invention relates to instantaneous carbonator apparatus.

An object of the invention is to provide an instantaneous carbonator apparatus in which maximum saturation of water with carbon dioxide gas is maintained regardless of varying time intervals between drafts.

Another object of the invention is to provide an instantaneous carbonator apparatus in which carbonated water is maintained within a predetermined volume range in a storage chamber through means of an electric system controlling operation of a motor for driving a pump that delivers water to the mixing chamber.

Another object of the invention is to provide an instantaneous carbonator apparatus in which the pressure of free gas is maintained only slightly above the set pressure of the incoming gas to thereby eliminate undue restriction to gas flow into the mixing chamber as required, and to maintain such pressure by relief of the free gas to the incoming gas.

A further object of the invention is to provide a carbonator apparatus having a refrigerated water intake conduit, leading to a chamber for mixture with carbon dioxide gas and also to a drinking water outlet with water supply means whereby water is automatically delivered to the intake conduit from a source under pump developed pressure when carbonated water is withdrawn from the apparatus and under lower pressure at the source when the pump is not operating and drinking water is withdrawn.

Another object of the invention is to simplify the water control means for an instantaneous carbonator apparatus to reduce the number of moving parts requiring service and renewal.

Other objects of the invention will appear from the following description taken in connection with the drawings, which form a part of this specification, and in which:

Fig. 1 is an elevational view, partly broken away, of a refrigerated carbonator mixing and storing structure incorporating a part of the invention;

Fig. 2 is a diagrammatic view of a complete instantaneous carbonator apparatus incorporating the invention.

In the illustrated carbonator apparatus, 10 designates generally the housing structure in which carbon dioxide gas and water are received, cooled, mixed and stored for draft. Such housing in many respects can be similar to that contained in my copending applications Serial Nos. 289,984 and 467,547, filed August 14, 1939, and December

2

1, 1942, respectively; now Patent No. 2,348,791 dated May 16, 1944, and Patent No. 2,401,915 dated June 11, 1946, respectively. An inner wall or tube 11 forms a chamber 12 and surrounding such wall in relatively close but spaced relation thereto is another wall or tube 13 forming chamber 14. Base ring member 15 is secured around the outside of the bottom portion of wall 13 and the upper end of wall 13 is turned inwardly to form a head 16 that is spaced above the top of wall 11. Because of this space between wall 11 and the head, chambers 12 and 14 will always be in open communication. The bottom of tube 11 is closed by an inverted cup shaped wall 17 that is secured thereto.

A metering and mixing device for carbon dioxide gas and water, indicated generally by numeral 20, includes a housing 21 that encloses the bottom of ring 15 and is secured thereto. Passage 20 in the housing is arranged to receive water and passage 24 in the housing is arranged to receive carbon dioxide gas. Check valve 25 controls water flow through passage 23 and check valve 26 controls gas flow through passage 24. Tube 27 extends from passage 23 to the top portion of the wall 17, the mixing chamber 28 being located within this wall and the top of housing 21. Partition 29 is secured on tube 27 below the openings 22 therein and its periphery is slightly spaced from the vertical portion of wall 17. Passage means 30 is formed in housing 21 to establish communication between gas passage 24 and the portion of chamber 28 below the partition. A stack of disks 32, having metering serrations 35 in their adjacent faces, lies between the outer portion of the partition and the housing 21 so that gas can flow outwardly into the water passing downwardly between the partition and the vertical portion of wall 17 to provide initial mixture. Such mixture will flow between housing 21 and the bottom edge of tube 11 and upwardly through narrow chamber 14 from which it flows over the top edge of tube 11 into chamber 12.

The source of carbon dioxide gas can be a cylinder 40 that is connected with passage 24 in the housing 21 of the mixing device by conduit 41. In conduit 41, adjacent to the gas cylinder, is a pressure regulator valve 42 and check valve 43 is also in the conduit between the regulator valve 42 and the mixing chamber. The check valve prevents back flow of the gas.

The source of water, indicated by numeral 45, can be a city supply reservoir or any other source from which water flows under relatively low pressure. Provision is made to mechanically or

otherwise refrigerate water flowing from the source of supply into the mixing device, and water inlet conduit means 46 can have a portion coiled around tube 13 and enclosed by a wall or tube 47 forming a refrigeration chamber 48. This chamber 48 can be closed at its bottom by ring member 15 and at its top by an inturned portion of tube 47 fixed to head 16. Inlet 49 and outlet 50 are suitably connected by conduits 67 and 68 respectively with a conventional mechanical refrigerating system so that refrigerant will pass through chamber 48 as required to maintain a suitable temperature for the water and the interior of the mixing and storage housing.

An outlet 51 for drinking water is connected to the conduit means 46 intermediate the portion in the refrigeration chamber and the water passage in the housing 21. The water inlet conduit means is connected with outlet conduit 53 leading from the source of water supply under low pressure by two conduits 54 and 55. Conduit 54 has a one way valve means 56 therein which opens away from the source and conduit 55 has a one way valve means 57 therein which closes toward the water entry end. A pump 58 is arranged in conduit 55 between the one way valve means 57 and outlet conduit 53, such pump being driven by a suitable electric motor 59 for raising the water pressure, when operating, above that of the water at the source of supply. If drinking water is drawn from conduit 51 while the pump is idle, the water supply would be inadequate because valve means 57 is closed, but as valve means 56 is open water will flow to the intake conduit means from the source of supply as it is withdrawn and thus draft of drinking water will not reduce the water supply when the pump is inactive. While the pump is operating valve means 57 will be opened and valve means 56 will be closed.

It is essential that water be supplied to the mixing and storage device in substantially the same volume as it is withdrawn by draft and the pump operation is controlled for this purpose by a floatless automatic electric control system associated with the pump motor. Such control means includes a pair of spaced electrodes 60 and 61 having their contact ends spaced vertically a suitable distance that will determine the high and low limits of the water level maintained in chamber 12. The electrodes are carried by a cylindrical body 62 formed of insulation material and having an axially extending outlet passage 63 therethrough. An outlet tube 64 is fixed to the outer end of the body by cap screw 65 and in communication with passage 63. The body projects part way through and is secured in collar 66 that is fixed to the head wall portion 16, the contact ends of the electrodes projecting into chamber 12 below the body.

Stainless steel wool 70 is provided in the chamber 12 and the electrodes are shielded from the wool by tube 71. The wool occupies the space in chamber 12 exteriorly of the tube and the tube has openings 72 adjacent the bottom of chamber 12 through which carbonated water can flow and maintain volume levels corresponding to those exterior thereof. An outlet conduit 74 is secured to the lower end of the electrode body in communication with passage 63 and the inlet end of such conduit lies adjacent wall 17.

The operation of electric motor 59 is controlled by a circuit established through conductors 81, 82 and 83. Conductor 81 leads to the motor from a suitable source of electric supply, conductor 83

is also connected with the source of electric supply and conductor 82 leads from the electric motor to a control station 84. The control station has suitable control mechanism therein for making and breaking the connection between conductors 82 and 83, such control mechanism being actuated through means of conductors 85 and 86 connected to electrodes 60 and 61. The fluid containing structure 10 is grounded by conductor 80.

The electrical control is arranged to cut out the electric circuit to the motor when the liquid level in chamber 12 contacts electrode 61 and to cut in when the fluid level in chamber 12 drops below electrode 60. The electrodes are preferably formed of material, such as stainless steel silver plated, to prevent their deterioration from electrolytic action. The shield 71 prevents the steel wool from contacting the electrodes and causing short circuiting, and such shield can be formed of plastic, glass or other suitable material.

Provision is made for a predetermined high pressure in chamber 12. Neck 90 can be fixed to head 16 and a needle valve 91 can be seated therein by spring 92 bearing against cap 93 screwed on the end of the neck. The adjustment of the cap will determine the spring pressure required to be overcome by gas pressure to open the valve.

Provision is also made for relieving pressure in the chamber 12 a little above set pressure in the gas inlet conduit and below that at which the blow off valve 91 will open, and for recirculating such outgoing gas through the mixing portion of the structure. Arm 96 extends from neck 90 below valve 91 and has a needle check valve 97 therein seated by spring 98 seated against a screw ring 99 adjustable to regulate the gas pressure required to open the valve. Conduit 100 leads from the arm 96 and is secured thereto by coupling 101, the conduit 100 being connected to the gas intake conduit 41 between check valve 43 and the mixing chamber.

Valve 42 is set to permit gas flow from cylinder 40 at some desired pressure, say 100 pounds per square inch, past valve 43 into the conduit 41. When carbonated water is withdrawn from chamber 12, pressure in the mixing and storage chambers drops below the gas pressure in conduit 41 and gas can flow into the mixing chamber past check valve 26. When the pump is operating, water will flow past check valve 25 into the mixing chamber and will raise the water level in the storage chamber. Some free gas will collect in the head of the chamber and the rising water will increase the pressure of such gas in the head above the set pressure in conduit 41 and so long as the head pressure is above the set pressure in conduit 41 no gas can pass by valve 26. Thus the carbonated water will not be fully saturated with gas, as gas will not flow into the mixing chamber with the water. When this head pressure is excessive, valve 91 will open for relief and this can occur when the apparatus is initially set up so that hand purging of air and/or gas is not necessary. Valve 97 is set to be opened by a pressure below that required to open valve 91 but above that of the set gas pressure in conduit 41. As an example, valve 97 can be set to open when there is a pressure of 102 pounds per square inch in the chamber 12.

The water and gas are thoroughly mixed prior to entering chamber 14 and the mixing continues as the mixture moves upwardly and flows into the top of chamber 12. The mixture must flow

downwardly through the steel wool in chamber 12 where gas clinging to the moist surfaces of the wool is picked up and mixed in with the mixture. The advantages of this mixing arrangement and the effect of refrigeration are more fully set forth in the previously mentioned applications.

As a further means of preventing undue pressure rise in the chamber 12, the carbonated water volume is maintained between two predetermined levels. The electrodes function to control the motor circuit so that the pump will automatically maintain a water volume in chamber 12 between two levels, as determined by the spaced relation of the contact ends of the electrodes. This arrangement will always provide sufficient carbonated water in chamber 12 to meet any sequence of drafts. By limiting the upper level of carbonated water in chamber 12, the pressure of free gas is limited so that valve 97 will have sufficient capacity to relieve pressure when it is required to open. Thus, this control also assists in holding down pressure in the head that would unduly hold the check valve 26 closed.

Gas flowing past valve 97 will enter conduit 41 and will raise the pressure therein momentarily so that gas will surge past check valve 26 when pressure in conduit 41 and chamber 12 becomes equalized. This surging of gas will insure a maximum inflow to the mixing chamber so that the water will be thoroughly saturated before draft even though there is a momentary delayed entrance.

By limiting the upper water level in chamber 12, a large surface area of steel wool will lie above the carbonated water. This large surface being wet and cold will immediately dissolve a large quantity of gas in contact therewith and, as the incoming mixture must trickle through this mass area, it will absorb its maximum volume of gas. The gas relieved through conduit 100 is recirculated with the incoming gas so that it is not wasted. The electric control of water eliminates previously used moving parts that required service and replacement. The carbonator structure will function fairly efficiently without the valve 97, but the use of such valve will aid in a better equalization of pressures in the storage chamber and conduit 41. Thus, the pump is not subjected to extreme pressure differential and a more uniform mixture of gas and water will be maintained.

It will be understood that various forms of the invention other than that described above may be used without departing from the spirit or scope of the invention.

What I claim is:

1. In a carbonator apparatus, a structure having a refrigerated chamber, a mixing chamber for water and carbon dioxide gas and a carbonated water storage chamber connected with the mixing chamber, a source of water under relatively low pressure, conduit means extending through the refrigerated chamber and connected with the mixing chamber, a check valve in the conduit means adjacent the mixing chamber, a drinking water outlet communicating with the conduit means between the refrigerated chamber and check valve, connecting means between the source of water under low pressure and the conduit means in advance of the refrigerated chamber, a second connecting means between the source of water and the conduit means in advance of the refrigerated chamber in parallel with the other connecting means, pump means in the second

connecting means, and means responsive to the liquid level in said storage chamber controlling operation of the pump means to maintain a predetermined volume range of carbonated water in the storage chamber.

2. In a carbonator apparatus, a structure having a refrigerated chamber, a mixing chamber for water and carbon dioxide gas and a carbonated water storage chamber connected with the mixing chamber, a source of water under relatively low pressure, conduit means extending through the refrigerated chamber and connected with the mixing chamber, a spring seated check valve in the conduit means adjacent the mixing chamber, a drinking water outlet from the conduit means between the check valve and the refrigerated chamber, means connecting the conduit means with the source of water supply, a check valve in said connecting means seated toward the source of water supply, a second means connecting the conduit means with the source of water supply, a pump in said second connecting means, a check valve in the second connecting means seated toward the pump, and automatic means controlling the pump operation to maintain a predetermined volume range of water in the storage chamber.

3. In a carbonator in which water and carbon dioxide gas are mixed to form carbonated water, a housing having a chamber in which the carbonated water flows downwardly, a head secured on the housing, a control unit for the volume of water in the carbonator having electrodes carried by a body formed of insulation material with a passage lengthwise therein, said body extending through and secured to the head with the passage open to the housing chamber, said electrodes having contact ends projecting into the chamber beyond the body, a tube secured to the body in communication with the inner end of the passage, said tube extending beyond the contact ends of the electrodes, and a carbonated water dispensing tube secured to the outer end of the body.

4. In an apparatus in which pumped water and carbon dioxide gas are mixed to form carbonated water, a housing forming a carbonated water storage chamber, a circuit control unit for controlling the volume of water pumped into the chamber having a body of insulation material and electrodes extending through the body, said body extending through and secured to the top of the housing and the electrodes extending into the chamber different distances beyond the body, and outlet means for the carbonated water in the chamber extending below the electrodes and through the body.

5. An apparatus in which water and carbon dioxide gas are mixed to form carbonated water, a housing forming a storage chamber into the head of which the mixture is introduced, a tubular shield in the chamber formed of insulation material and open adjacent its bottom portion to receive carbonated water from the chamber, electrodes in the tube having contact ends extending different distances toward the bottom of the chamber, steel wool filling the chamber exteriorly of the tube, water dispensing conduit means open to the bottom portion of the tube, a pump for supplying water for mixture with the gas, an electric motor for operating the pump, and an electric circuit controlled by said electrodes for starting and stopping the motor.

6. In a carbonator, four telescoped shells forming four chambers, the inner shell being formed of insulation material and having an opening adjacent the bottom, steel wool in the chamber ad-

7 jacent the inner chamber, the two intermediate chambers communicating at their top portions, cover means on the next to the outside shell extending over the two inner shells, means supplying carbon dioxide gas and water to the bottom portion of the chamber adjacent the outside chamber, means refrigerating the outside chamber, and an outlet for carbonated water leading from the inner chamber through the cover means.

7. In a carbonator, three telescoped shells forming three chambers, the inner shell having an opening adjacent the base portion, steel wool in the intermediate chamber, top cover means on the outer shell extending over the inner shells, means supplying carbon dioxide gas and water to the bottom of the outer chamber, said outer chamber and intermediate chambers communicating at their top portions, a carbonated water outlet means extending into the inner chamber through the cover means and open thereto adjacent the bottom portion, and water supply con-

8 trol means in said inner chamber carried by the outlet means.
